UNITED STATES PATENT OFFICE.

ERWIN NELSON WOODWARD, OF GROTON, NEW YORK, ASSIGNOR TO
WILLIAM L. PIKE, OF SAME PLACE.

WRENCH.

SPECIFICATION forming part of Letters Patent No. 536,312, dated March 26, 1895.

Application filed December 7, 1894. Serial No. 531,087. (No model.)

To all whom it may concern:

Be it known that I, ERWIN NELSON WOODWARD, a citizen of the United States, and a resident of Groton, county of Tompkins, and State of New York, have invented certain new and useful Improvements in Wrenches, of which the following is a specification, reference being had to the accompanying drawings, forming a part thereof, in which similar letters of reference indicate corresponding parts in both figures.

This invention relates to wrenches particularly such as are used for grasping square, hexagonal or similarly shaped wagon and other nuts of various sizes, and has for its object to provide a device of this character which will be simple, cheap, and perfectly operating, and which may be constructed of two malleable iron or other castings.

The invention consists in the novel construction and arrangement of parts herein-after more fully described.

In the accompanying drawings: Figure 1 is a plan view of a device embodying my invention. Fig. 2 is a longitudinal section of the same taken upon the line $x-x$.

In the practice of my invention, I construct a strip or plate of metal A, having at the rear end thereof an enlargement or head B, in the end and each side of which are formed rectangular openings or recesses B', B², B³, of different widths and depths. This head B serves a double purpose of enabling, without manipulation, the engaging of nuts which approximately fit either of the apertures B', B², B³, and at the same time a more secure grasping or handling of the wrench, forming a handle therefor and also acting as a knob to prevent slipping thereof from the hand.

At the opposite or forward end of the plate A is a curved and upwardly projecting integral extension or arm C, sectionally V-shaped to form shoulders a ranging diagonally at right angles to each other from the center of the forward end of the wrench.

From the forward end of the plate A to a point beyond the center thereof is formed, in the upper face of the plate, a longitudinal groove A', curved at the rear end thereof and of such width as to leave thin or shell-like side edges A²; the construction of the plate

A and its arm C being such that the shoulders a are of substantially equal thickness with, and in effect a continuation of, the said side edges A². Sliding upon the said edges A² 55 is a plate or section D having a central elliptical shoulder b upon the under face thereof, which slides in the groove A'; and upon each side of said plate are formed outwardly extending and downwardly projecting flanges 60 D' which engage or clasp the outside of the edges A². The sliding plate D has upon the forward end thereof an arm C', shaped and constructed similarly to the arm C, but having the shoulders a thereof projecting from 65 their junction diagonally forward.

Extending through the center of the plate D and the shoulder b thereon is a square opening c, immediately in alignment with which, the plate A has formed therein at the bottom 70 of the groove A' an elongated slot c'. Through the opening c, I insert a bolt E, having the upper portion d of its shank sectionally square, and surmounted by an enlarged flat head e, the remainder of the bolt being reduced in 75 diameter and the lower half thereof screw-threaded. This latter portion of the bolt extends through, and slides longitudinally in, the slot c' in the plate A, and has removably secured thereon a thumb-nut F, having a flat 80 and enlarged under face f to project beyond the edges of said slot and frictionally engage the plate A.

The operation of the device will be readily understood from the foregoing description 85 taken in connection with the accompanying drawings. The thumb-nut F being loosened, the wrench is grasped by the handle or main portion of the plate A and the head B, and the shoulders a of the arm C placed against 90 the nut operated on to engage the same. The sliding plate D is then forced forwardly to bring the shoulders a thereon in engagement with the opposite portion of the nut, this sliding or reciprocation of the plate being effected 95 either through the side flanges D' or preferably by grasping the thumb-nut F; and when the said plate D is projected as far as the size of the nut will permit, a single turn is given the said thumb-nut; which thereby clamps 100 the said plate upon the edges A², and the shoulder b thereof against the base of the

groove A', said thumb-nut itself frictionally engaging the under surface of the plate A, thereby preventing any slipping or yielding of the plate D, whereupon the operation of turning the nut is performed in the usual manner. As before stated, the recesses B', B² and B³ permit the turning, without manipulation of the wrench, of any nuts which approximately fit either of the same, and thus 10 the utility of the tool is enhanced.

The advantages resultant from the use of my invention will be manifest to all who are conversant with the general class of devices to which the same appertains.

15 I do not confine myself to the exact formation of parts or details herein set forth and illustrated.

Having thus fully described my invention, what I claim as new, and desire to secure by 20 Letters Patent, is—

1. A wrench comprising a main body or plate, having an integral curved arm projecting upwardly therefrom at one end, and provided with angular, sectionally V-shaped shoulders, arranged at right angles to each other, a longitudinal groove formed in said body from the end to center of the same, a slot formed in said body at the bottom of the groove, a smaller plate or section sliding upon 25 the body, and having an integral upwardly projecting arm, provided with similar V-shaped opposing shoulders, longitudinal flanges upon each side of the section, clasping the edges of the plate, and an integral elliptical shoulder upon the under surface thereof, sliding in the groove, said section and shoulder having an aperture projecting therethrough, a bolt inserted through said aperture and the slot in the plate, and a thumb-nut 30 mounted upon the bottom of the said bolt, and adapted to frictionally engage the under surface of the main body to secure the sliding section at any desired adjustment, substantially as shown and described.

45 2. A wrench comprising a plate or body, having an integral curved arm projecting upwardly therefrom at one end, and provided with angular, sectionally V-shaped shoulders, arranged at right angles to each other, a longitudinal groove formed in said body from 50 the end to center of the same, a slot formed in said body or plate at the bottom of the groove, a smaller plate or section sliding upon the body, and having an integral upwardly projecting arm provided with similar V-

shaped opposing shoulders, longitudinal flanges upon each side of the section projecting downwardly and clasping the edges of the plate, and an integral elliptical shoulder upon the under surface thereof sliding in the 60 groove, said section and shoulder having a square aperture projecting therethrough, a bolt inserted through said aperture and the slot in the plate, having a square shank to prevent turning thereof, and a flat enlarged 65 head, and a thumb-nut mounted upon the lower end of said bolt, projecting beyond the slot to engage the undersurface of the wrench-body and secure the sliding section at any desired adjustment, said thumb-nut being 70 adapted to serve as a handle to reciprocate the sliding section, substantially as shown and described.

3. A wrench comprising a plate or body having an integral curved arm projecting upwardly therefrom at one end and provided with angular, sectionally V-shaped shoulders, arranged at right angles to each other, a longitudinal groove formed in said body from the end to center of the same, rounded at the 80 rear, a slot formed in said body or plate at the bottom of the groove, and a flat integral extension or handle upon the rear end thereof, having varying nut-holes in each side thereof, a smaller plate or section sliding upon the 85 body and having an integral projecting arm provided with similar V-shaped opposing shoulders, longitudinal flanges upon each side of the section clasping the edges of the plate, and an integral elliptical shoulder upon the 90 under face thereof, sliding in the groove, said section and shoulder having a square aperture projecting therethrough, a bolt inserted through said aperture and the slot in the plate, having a square shank to prevent turning 95 thereof and a flat enlarged head, and a thumb-nut mounted upon the lower end of said bolt, projecting beyond the slot to engage the under face of the wrench-body and secure the sliding section at any desired adjustment, 100 substantially as shown and described.

In testimony that I claim the foregoing as my invention I have signed my name, in presence of two witnesses, this 4th day of December, 1894.

ERWIN NELSON WOODWARD.
